ANTISKID DEVICE

Charles Bernard Pittinger, Baltimore, Md.

Application March 2, 1950, Serial No. 147,284

3 Claims. (Cl. 152—216)

1

The present invention relates to an anti-skid device and in particular to an improved automatic or semi-automatic type.

The primary object of the invention is to provide an improved anti-skid device which may be folded and carried by means secured to the wheel and the vehicle frame when not in use and be in a position to be automatically applied to the wheel when it is required, or desirable.

Another object of the invention is to provide new and novel means for removing and applying the anti-skid elements to the vehicle wheel.

A further object of the invention is to provide a device with automatic means for keeping the device in a retracted position when not in use.

A still further object of the invention is to provide new and novel means for moving the anti-skid elements about the circumference of the vehicle wheel.

While several objects of the invention have been pointed out, other objects, advantages, and uses will become more apparent as the nature of the invention is more fully described, which consists in the novel construction, combination and arrangement of parts shown in the accompanying drawings and described in the following detailed description, in which:

Figure 1 is a fragmentary view of a vehicle in side elevation showing a wheel and the anti-skid device in operating position.

Figure 2 is a view similar to Figure 1 showing the anti-skid device in retracted position.

Figure 3 is a fragmentary elevational sectional view on a small scale of the vehicle wheel along line 3—3 of Figure 1.

Figure 4 is a sectional view taken along line 4—4 of Figure 6.

Figure 5 is a sectional view taken along line 5—5 of Figure 6.

Figure 6 is a sectional view taken along line 6—6 of Figure 5 showing a support and mechanism for operating the anti-skid supporting members.

Figure 7 is a view in elevation of one of the ring gear plates.

Figure 8 is an enlarged fragmentary plan view of the outer surface of the element operating mechanism.

Figure 9 is a fragmentary sectional view taken along line 9—9 of Figure 7.

Figure 10 is an enlarged fragmentary sectional view taken along line 10—10 of Figure 6.

Figure 11 is a wiring diagram for the operating means for the arm members.

In the drawing there is shown in Figure 1 a 55 is connected by a belt or chain 43 with a worm

2

vehicle wheel 14 and a pneumatic tire 15. Arranged upon an outer support, or mechanism, rotatably secured to the outside hub of the wheel and an inner support 26, are a plurality of anti-skid element supporting arm members 18, 18' and 18''. These supporting members are adapted to automatically position the anti-skid elements about the tire tread 15 and likewise to retract the elements to a position which will be out of contact with the road and not interfere with the normal rotation of the wheel.

The anti-skid or traction elements 20, 20' and 20'' are arranged in circumferentially spaced relationship about the periphery of the tire 15. These elements are normally retained out of contact with the wheel tread so that the wheel may rotate freely when the device is out of operating position. The traction elements are preferably constructed of a chain imbedded in rubber in order that they may take a U-shaped form about the tread of the tire and be lifted therefrom by the movement of the supporting arms 18. The anti-skid elements have one of their ends secured to the outside arm members 18, 18' and 18'' and their other ends attached to an eye member 22 in one of the inner free rotating members 24. These members 24 are of a centerless band design and so mounted on the member 26 as to be independently and freely slidable in relation to each other and are movable by the elements 20 which are, in turn, moved by the outside supporting arms 18, 18' and 18''.

The anti-skid elements 20, 20' and 20'' are carried upon one end of each of the outer operating arms 18, 18' and 18'' and the inner ends of the elements are connected to one of the free rotating disks 24. In Figure 1 the anti-skid elements are shown in extended, or operating position, and in Figure 2 they are shown in a collapsed position or in non-operating position.

The arms 18, 18' and 18'' are utilized for moving the anti-skid device into and out of operating and non-operating position. The means for operating the arms 18, 18' and 18'' are located on the outer wheel hub and is rotatably supported thereon by the bearings 30. The bearings 30 are supported to the wheel hub by the bracket 32, which is bolted to the hub by the bolts 34. Rotatably supported on the bracket 32 is an inner bearing support 35 and to this member there is fixedly secured a rear supporting side plate 36. On the opposite side of the operating means is an outer side plate 37. Fixedly secured to the side plate 37 is a small motor 38, which in turn

and a gear 44 for driving the operating means. Extending perpendicularly to the face of the wheel and axially of the plates 36 and 37 is a shaft 42 fixedly secured to the inner bearing support 35 at 42'. The gear 44 is secured to an extended portion 36' of the side plate 36 and is adapted to mesh with the worm 40. Keyed to the portion 36' is a spur gear 46. This spur gear 46 is adapted to engage a spur gear 48, of which there are three, 48, 48' and 48''. These gears are rotatably supported upon the plate 37 by the bearings 49, 49' and 49''. These gears 48 are of such a width as to engage a driven disk or an internally toothed ring gear 50 and a plurality of smaller spur gears 52, 52' and 52''. The spur gears 52, 52' and 52''' in turn engage another driven disk or internal toothed ring gear 54. Lying between the internal gear ring 50 and the rear plate 36 are five freely rotatable disk members 56. The five disks and the ring gear members make up a total of seven members corresponding to the number of links made between the arms 18 and the operating mechanism.

The driving means is preferably an electric motor which is connected with the worm gear shaft 41 by a chain or belt member 43. The motor is of the reversible type and is adapted to be controlled from the dash board by a suitable switch 60. The wiring and details of such motors are well-known in the art. For example, with the switch lever 60 in off position, the lever is moved to on position, the motor will operate to apply the anti-skid members, and when in off position, the motor is reversed and the anti-skid elements are retracted.

As previously stated, the arms 18, 18' and 18'' are each attached to either the member 50, 54, or to one of the free rotating disks 56 located between the ring gear 54 and the rear plate member 36. For attaching the arms 18, 18' and 18'' to the outside of the wheel, there is provided lugs 62, 63, 64, 65, 66, 67 and 68. Lugs 62 to 66 are carried on the free rotation disks 56. The lug 67 is carried on the internal ring gear 50 and the lug 68 is carried on the internal ring gear 54. These ring gears are so geared that they will operate in opposite directions. The arms 18 are pivotably attached to each adjacent arm and to a lug at a point substantially midway between its connecting points with the other adjacent arm members, one end of each arm extending slightly beyond the point of connection with one of the adjacent arms for receiving one of the anti-skid elements 20. The anti-skid elements are normally held parallel with the arms 18 when not in operating position as shown in Figure 2. This may be done by any well-known conventional coiled spring (not shown).

Positioned on the outer end of the shaft 42 is a tubular member 70. This member is rotatably mounted upon the bearings 51 and extends either forwardly or rearwardly to the body of the vehicle and is connected therewith by a flexible portion 70'. This tubular member carried the control wires that lead from the dash to the motor 38. The tube 70 has also a recess for receiving a latch 72 which is carried by the ring gear 54 for positioning the anti-skid elements when they are in their retarded position as shown in Figure 2.

The last disk member 56 is connected with the ring gear 54 by a bracket 75 as shown in Figure 8.

The latch member 72 is fixed secured to the ring gear 54 and rotates therewith. There is a

loaded spring plunger 76 carried within the latch 72. This plunger is movable longitudinally of the latch and through an aperture 77 within the ring gear 54 to engage a slot 78 within the ring 50. This slot extends substantially the entire distance around the ring gear 50, as shown in Figure 7. The slot 78 does not continue entirely around the ring gear 50 as shown in Figures 7 and 9 at 79. This portion 79 is so located about the gear ring that it will be opposite the tubular member 70 when the anti-skid members are retracted in the position as shown in Figure 2. At this point the portion 79 of the ring gear 50 presses the loaded pin outwardly as shown in Figure 6, which is adapted to engage an aperture 80 located adjacent the outer end of the tubular positioning member 70 and retain the restricted anti-skid elements in a position where they will be out of contact with the road surface and at a convenient carrying place in relation to the vehicle.

In Figure 11 is shown diagrammatically a mechanism for automatically cutting out the motor 38 when the device is either fully retracted or fully expanded to operating position. The construction of this cut-out is, that the worm 40 is slidably mounted upon a pair of suitable bearings 81 and 81' and is held centrally by a pair of spring members 82 and 82'. Extending inwardly from the bearings 81 and 81' is a bracket 83 upon which is rotatably mounted the shaft 41 supporting the worm 40. The springs 82 and 82' hold the worm and bracket 83 centrally of the bearings 81 and 81'. The bracket is slidably fixed to a supporting plate 39 by the screws 84 and 84'. Fixedly secured to the member 83 is a finger 85, which is in the path of two electric spring switches 86 and 86'. When either one of these switches are depressed, the circuit through that electric lead will be broken. In normal operation, the spring members 82 and 82' will retain the finger 85 out of contact with the switch, as shown in Figure 11. When the arms 18 have been fully collapsed and the worm 44 is stopped by this resistance, the extra pressure will cause the worm 40 to move against one of the springs 82 or 82', which will also move the bracket and finger 85 in contact with one of the switch members 86 or 86' and will break the circuit to a conventional relay and shut off the current to the motor 38. The opposite procedure will occur when extending the anti-friction element to operating position.

Operation

Beginning with the anti-skid element in retracted position as shown in Figure 2, when the switch 60 on the dash-board is turned to "on" position, current will flow through a relay (not shown) and wires 90 and 91 (Figure 11) to the motor 38 which will by way of the chain or belt 43 operate the worm and worm-gear which in turn will operate the ring gears 50 and 54 in opposite directions.

As the ring gears 50 and 54 are rotated in opposite directions, the plunger 76 will drop into the slot 78 and release the latch 72 from the aperture 80 within the tubular arm member 70. This will allow the anti-skid elements to rotate with the wheel while they are being applied. When the ring gears have rotated to a point in which the lugs 67 and 68 are in contact, the resistance on the worm-gear 44 will move the worm and bracket 83 together with the finger 85 toward the switch 86 sufficiently to break the cir-

cuit to the relay which will in turn break the circuit to the motor. The opposite procedure will occur when it is desired to retract the elements. When the lever 61 of the dash-board switch 60 is moved to the "off" position, current will flow to the motor 38 through a relay and wires 90 and 93 for rotating the motor in the opposite direction which will move the ring gears 50 and 54 in reverse directions as just described for applying the elements. As the arms 18' and 18'' are positively moved by the lugs 67 and 68 carried by the ring gears 50 and 54, the arms 18 carried on the free-floating disks 56 will be folded evenly about the wheel as the lugs 67 and 68 move to their limited closed position. In Figure 2 the lugs 67 and 68 are shown reaching their limit when the arms 18 will become fully collapsed and fully abutted together. When the worm-gears 49 and 44, together with the bracket 83 and the finger 85, are moved in the direction of the switch 86', the switch will be thrown which will deenergize the relay (not shown) and break the circuit to the motor 38. When the ring gear 50 has been rotated to a predetermined point in relationship to the ring gear 54, the loaded plunger 76 of the latch 72 will be forced outwardly by the portion 79 and will engage the aperture 80 adjacent the outer end of the tubular member 70 for retaining the anti-skid members in a position where they will not be in contact with the road surface as shown in Figure 2.

As previously stated, the free-floating rear disks 24 are moved by the action of the anti-skid members which are in turn moved and regulated by the ring gears 50 and 54 and the action of the arm members 18 with the free-floating disks 56 carried on the outer end of the hub.

The device is bolted to the hub by the studs 34 and rotates freely and independently on the bearings 30 and can be easily removed when it is necessary to change tires or do other mechanical work to the wheel.

While the invention has been illustrated and described in a particular form, it is not intended to be a limitation of the invention and the scope of the invention is best defined in the accompanying claims.

I claim:

1. In a traction device for a vehicle wheel, comprising a plurality of anti-skid elements arranged in spaced relationship about the tread of the wheel, a free rotating positioning means for supporting the elements along and adjacent the tread of the wheel, means for simultaneously moving the elements radially and circumferentially to a collapsible position at a predetermined fixed location adjacent the upper portion of the wheel, said element moving means comprising an operating unit having an electrically operated gear mechanism rotatably supported adjacent the outer surface of the wheel including a plurality of disks having a common axis carried by said unit, two of the said disks being in the form of internal ring gears adapted to be rotated by the said gears in opposite directions, means for pivotably connecting two adjacent arms to each of the rotated disks and means for connecting each of the remaining arm members to a separate free-floating outer disk and to each other, means adjacent one end of the said arm members for pivotably receiving one end of the anti-friction elements and means located on the inner side of the hub for supporting a plurality of free-

floating disk elements and means on each of the said inner disks for pivotably attaching the opposite ends of the anti-friction elements thereto.

2. In a traction device for a vehicle wheel, comprising a plurality of anti-skid elements arranged in spaced relationship about the tread of the wheel, a free rotating positioning means for supporting the elements along and adjacent the tread of the wheel, means for simultaneously moving the elements radially and circumferentially of the wheel to a collapsible position at a predetermined fixed location adjacent the upper portion of the wheel, said element moving means comprising an operating unit having an electrically operated motor and a reduction gear rotatably supported adjacent the outer surface of the wheel, including a plurality of disks having a common axis carried by said unit, two of the said disks adapted to be rotated by the said motor in opposite directions relative to each other and connecting link arm members pivotably connected to an individual disk member and to each other, means adjacent one end of the said arm members for pivotably receiving one end of the anti-friction elements and means located on the inner side of the hub for supporting a plurality of free-floating disk elements and means on the said inner disks for pivotably attaching the opposite ends of the anti-friction elements, a positioning arm, a latch carried by one of the driven disks, means associated with the positioning arm for receiving a plunger carried by the said latch for positioning the anti-friction elements in a predetermined location.

3. An anti-skid device for a vehicle wheel, comprising a plurality of anti-skid elements arranged in spaced relationship about the tread of the wheel, means for rotatably supporting the elements adjacent the tread of the wheel, means for simultaneously moving the elements radially and circumferentially of the wheel to a collapsible position at a predetermined fixed location adjacent the upper portion of the wheel, said element moving means comprising an operating unit having an electric motor driven gear rotatably supported upon the hub of the wheel, a plurality of disks having a common axis carried by said unit, two of the said disks adapted to be rotated by the said motor in opposite directions relative to each other, connecting link members pivotably connected to individual disk members including the driven disks and to each other, means adjacent one end of the said arm members for pivotably receiving one end of the anti-friction elements and means located on the inner side of the hub for supporting a plurality of free-floating disk elements and means on the said inner disks for pivotably attaching the opposite ends of the anti-friction elements and means for automatically keeping the anti-friction elements in either operating or retracted position.

CHARLES BERNARD PITTINGER.
